UNITED STATES PATENT OFFICE.

CYRUS W. SALADEE, OF TORRINGTON, CONNECTICUT.

SIDE-SPRING VEHICLE.

SPECIFICATION forming part of Letters Patent No. 274,390, dated March 20, 1883.

Application filed June 15, 1882. (No model.)

To all whom it may concern:

Be it known that I, CYRUS W. SALADEE, a citizen of the United States, and a resident of Torrington, in the county of Litchfield and State of Connecticut, have invented certain new and useful Improvements in Vehicles, of which the following is a specification.

My invention consists in a new and improved mode of constructing and applying side springs to vehicles, as hereinafter fully described, and has for its object to admit of the vertical movement of the body without tilting, while carrying the body at a point directly below the cross-center of the seat.

In the drawings, Figure 1 is a side elevation of so much of a buggy as is necessary to show my invention applied. Fig. 2 is a plan view of the bottom of the body and gear, and Fig. 3 is a diagram to illustrate the main points of improvement secured by my invention.

By reference to Fig. 3 it will be seen that the vertical line N coincides with the center of the body midway between the axles, and with the central point of attachment of the spring, and that line O coincides with the center of the seat. As the weight carried in these vehicles is on the seat, the line O will indicate to what extent the load must be back of the point of attaching the spring to the body, and shows that the spring does not support the body at that point where the greatest part of the load is carried, and hence the liability (so common in this class of wagons) of the rear end of the body to hang or sag lower than the front end when loaded and in motion. I overcome this defect by giving to the rear half of the spring substantially the form seen in Fig. 1, whereby to project the spring farther to the rear, and support the rear half of the body directly under the seat on the line O. The side spring is made of two sections, as shown, or in one piece, and by extending the spring back of the axle and turning it to its point of suspension to the rear of the axle length is secured to insure a safe and easy spring-support. The front section, D, of the spring cannot be of the same form as the rear section, as in that case it would be struck by the front axle as the lat-

ter is turned in turning the vehicle. This section therefore must be of substantially the form of a true semi-elliptic spring. If this latter form were duplicated for the rear half of the spring, it would necessitate the use of a link to admit of the elongation of the spring under pressure; but in the construction shown the curved end of the rear half, C, of the spring permits the elongation of the spring and a free and easy vertical movement of the body. The front ends of the springs are jointed to immovable shackles on the front bar, and the rear ends to immovable pivots at the rear of the rear axle, thus permitting vertical motion of the body, but no tilting thereof.

I propose sometimes to use the rear sections, C, Fig. 1, but with a cross-spring, D'. (Shown in dotted lines.) Said cross-spring may be of any suitable character, and applied to the side bars and body in the usual way. These springs are equally well adapted to either the ordinary "side-spring" or to the "side-bar" gears now in general use, and I intend to use them in both classes of wagons.

I claim—

1. The combination, in a vehicle, of a body, frame, and side springs having a greater length between their points of suspension than the distance between the bolster and axle, and connected to the body to support the same at a point nearest the rear end, with the front ends pivoted to stationary shackles and rear ends pivoted at the rear of the rear axle, substantially as set forth.

2. A vehicle having side springs, each in two sections, the front sections bent to substantially true semi-elliptical form and pivoted to stationary shackles, and the rear sections bent to a double sweep and pivoted at the rear of the axle, substantially as set forth.

In testimony whereof I have signed my name to this specification in the presence of two subscribing witnesses.

CYRUS W. SALADEE.
